(57) **CLAIM**

The ornamental design for a male catheter connector, as shown and described.

DESCRIPTION

FIG. 1 is a perspective view of a male catheter connector showing my new design;

FIG. 2 is another perspective view thereof from a substantially opposite direction;

FIG. 3 is a rear elevation view thereof;

FIG. 4 is a front elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines immediately adjacent the shaded areas represent the bounds of the claimed design and form no part thereof.
